UNITED STATES PATENT OFFICE.

JOHN E. COLES, OF CANARSIE, NEW YORK.

TWINE-HOLDER.

SPECIFICATION forming part of Letters Patent No. 393,619, dated November 27, 1888.

Application filed March 6, 1888. Serial No. 266,382. (No model.)

To all whom it may concern.

Be it known that I, JOHN E. COLES, a citizen of the United States, residing at Canarsie, Long Island, Kings county, State of New York, have 5 invented certain new and useful Improvements in Twine-Holders, of which the following is a full, clear, and exact specification, reference being had to the accompanying drawings, forming a part thereof.

10 My invention relates to certain improvements in devices for holding twine, and particularly designed for use in stores; and the object of my present improvement is to provide a twine-holder adapted for attachment beneath 15 the desk or counter entirely out of the way, and having means whereby the twine is brought into an exposed position for convenient handling when required. This object I accomplish by the construction and arrangement shown in 20 the accompanying drawings, in which—

Figure 1 is a side elevation of my improved twine-holder, shown attached to the under side of a counter; and Fig. 2 is an end view of the same, taken from the front.

25 Let *a* represent an open cup shaped receptacle adapted to hold a ball of twine, *b*. Extending from the upper part of this receptacle is a long arm, *c*, which is provided with a V-shaped opening, *d*, leading into the receptacle, 30 through which the twine is led out to the front of the counter, where it is convenient for use whenever required. On each side of the arm *c* is provided an outwardly-projecting flange, *e*.

f is a hanger adapted to hold the arm *c* and permit of its sliding therein, being formed with 35 a recess to correspond to the under part of the arm, and having offsets *h h* to serve as bearings for the flanges *ee*, so that the twine-holder may slide to and fro therein. The hanger-piece *f* is secured to the under side of the 40 counter *k* by means of screws *i i*, passing through the flanges *j j*. As shown in Fig. 1, the top of the receptacle, after the ball of twine 45 is placed therein, is set up close to the under side of the counter, with the end of its arm 50 coming flush with the front of the same, so that it is entirely out of the way, while the end of the twine is in a position to be readily taken in the hand. When it becomes necessary to replenish the twine, it is only required to slide 55 the holder out from its hanger, when access may be readily had to its interior.

Having described my invention, what I claim as new, and desire to secure by Letters Patent, is—

55 The receptacle *a*, having grooved arm *c*, provided with flanges *ee*, combined with the hanger *f*, provided with the offsets *h h*, as shown and described.

JOHN E. COLES.
